DESIGN FOR A CONTAINER FOR TOYS AND THE LIKE

T. Barry Hodge, Chicago, Ill.

Application July 18, 1945, Serial No. 120,782

Term of patent 7 years

(Cl. D58—12)

To all whom it may concern:

Be it known that I, T. Barry Hodge, a citizen of the United States of America, residing at Chicago, in the county of Cook and State of Illinois, have invented a new, original, and ornamental Design for a Container for Toys and the like, of which the following is a specification, reference being made to the accompanying drawings, forming a part thereof.

Fig. 1 is a top and side perspective view of a container for toys showing my new design;

Fig. 2 is a bottom and side perspective view thereof.

I claim:

The ornamental design for a container for toys and the like, substantially as shown.

T. BARRY HODGE.
